(57) **CLAIM**

The ornamental design for an AR 15 dressing kit, as shown and described.

DESCRIPTION

FIG. 1 is a front perspective view of an AR 15 dressing kit, showing our new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is a rear perspective view thereof;

FIG. 9 is another rear perspective view thereof; and,

FIG. 10 is another front perspective view thereof.

The broken lines represent unclaimed portions of the design article. All of the broken lines forms no part of the claimed design.
